UNITED STATES PATENT OFFICE.

WALTER SIMPSON, OF PROVIDENCE, RHODE ISLAND, ASSIGNOR TO THE FIRM OF
WALTER SIMPSON COMPANY, OF PROVIDENCE, RHODE ISLAND, COMPRISING
WALTER SIMPSON, OF PROVIDENCE, RHODE ISLAND, AND FRANK E. GUILD, OF
ATTLEBORO, MASSACHUSETTS.

DESIGN FOR A REFRIGERATOR DISPLAY-CASE.

49,285.

Specification for Design. Patented June 27, 1916.

Application filed April 3, 1916. Serial No. 88,732. Term of patent 7 years.

To all whom it may concern:

Be it known that I, WALTER SIMPSON, a citizen of the United States, residing in the city and county of Providence, State of Rhode Island, have invented a new, original, and ornamental Design for a Refrigerator Display-Case, reference being had to the accompanying drawing, forming a part thereof.

Figure 1— is a perspective view of my

refrigerator display case illustrating my new design. Fig. 2— is an end view of my refrigerator display case.

I claim:

The ornamental design for a refrigerator display case, as shown.

WALTER SIMPSON.
